UNITED STATES PATENT OFFICE.

JOSEPH SCHOENFELD, OF ALAMEDA, CALIFORNIA, ASSIGNOR TO THE MAGNAVOX CO., OF OAKLAND, CALIFORNIA, A CORPORATION OF ARIZONA.

DESIGN FOR AN ELECTRIC-HEATER STAND.

Application filed September 13, 1924. Serial No. 10,769. Term of patent 14 years.

To all whom it may concern:

Be it known that I, JOSEPH SCHOENFELD, a citizen of the United States, residing at Alameda, in the county of Alameda and State of California, have invented a new, original, and ornamental Design for Electric-Heater Stand, of which the following is a specification, reference being had to the accompanying drawing, forming part thereof.

Fig. 1 is a perspective front view of an electric heater stand.

Fig. 2 is a side elevation of the same.

I claim:

The ornamental design for an electric heater stand, as shown.

JOSEPH SCHOENFELD.
